CLAIM

The ornamental design for a wearable information terminal, as shown and described.

DESCRIPTION

FIG. 1 is a front, right side, bottom perspective view of a wearable information terminal showing my new design; FIG. 2 is a front elevational view thereof; FIG. 3 is a rear elevational view thereof; FIG. 4 is a left side view thereof; FIG. 5 is a right side view thereof; FIG. 6 is a top plan view thereof; FIG. 7 is a bottom plan view thereof; FIG. 8 is a reference perspective view thereof, with a wristband attached; and, FIG. 9 is a reference front elevational view thereof, showing an example of a used state.

The broken lines showing portions of the article illustrate environmental structure only and form no part of the claimed design.

1 Claim, 8 Drawing Sheets(56)
